UNITED STATES PATENT OFFICE.

THOMAS SHINGLER, OF DETROIT, MICHIGAN, ASSIGNOR TO EASTMAN MACHINE COMPANY, OF BUFFALO, NEW YORK.

CLOTH-CUTTING MACHINE.

1,218,007.

Specification of Letters Patent.

Patented Mar. 6, 1917.

Application filed September 19, 1916. Serial No. 120,939.

To all whom it may concern:

Be it known that I, THOMAS SHINGLER, a citizen of the United States, residing at Detroit, in the county of Wayne and State 5 of Michigan, have invented a new and useful Improvement in Cloth-Cutting Machines, of which the following is a specification.

This invention relates to portable cloth 10 cutting machines of the kind that are adapted to be moved about by hand on a cutting table and have a motor driven knife which reciprocates in a guide in the vertical standard by which the motor is supported from 15 the base of the machine. In cutting some kinds of material, such, for instance, as rubberoid, the knife becomes sticky or gummed by contact with the material, and this increases the friction of the knife in 20 its guide to such an extent as to greatly impede the operation of the machine.

The object of the invention is to obviate this difficulty by providing machines of this kind with a lubricating device of simple 25 and practical construction which will effectually lubricate the knife so as to prevent it from working hard in its guide.

In the accompanying drawings:

Figure 1 is a fragmentary side elevation, 30 partly in section on line 1—1, Fig. 2, of a cloth cutting machine embodying the invention.

Fig. 2 is a front elevation partly in section thereof, the knife being removed.

Fig. 3 is a side elevation, partly in section, of the lubricating device detached 35 from the machine.

Fig. 4 is a sectional elevation on line 4—4, Fig. 2.

Fig. 5 is a sectional plan view on line 40 5—5, Fig. 4.

With the exception of the means herein-after described for lubricating the knife and its guide, the machine may be of any 45 suitable construction, and an electric cloth cutting machine of well known construction is illustrated in the drawings.

The machine has the usual base A adapted 50 to rest and move on the cutting table beneath the material to be cut, a vertical standard B which rises from the base and supports an electric motor C, and a knife D which is reciprocated vertically by suitable driven connections E with the motor. 55 The knife, as usual, reciprocates in a verti-

cal guide or slot F in the front edge of the standard B. In the machine shown in the drawings, a hollow frame or housing G surmounts the standard B, being secured on a horizontal extension g of the upper end 60 of the standard, and the motor C is secured on this frame G.

The lubricating means for the knife and its guide are preferably constructed and arranged as follows:

10 indicates a cup or reservoir mounted on one side of the housing G and adapted to contain a suitable oil or liquid and feed the same in a suitably regulated manner to the knife. A sight-feed oil cup of ordinary 70 construction is shown having a drip nozzle 11 controlled by a valve which can be adjusted to cause the oil to drip at suitably regulated intervals, determined by the adjustment of the valve. The oil cup is secured on a tubular connection 12 which is secured preferably detachably, by means of screws 13, on one side of the hollow frame G and extends upwardly and outwardly 75 therefrom. A feed tube 14 extends from the discharge nipple of the oil cup through a hole 15 in the side wall of the frame G and its lower end extends into or through a hole 16 in the front wall of the frame, terminating so as to drip into a flaring 80 groove or notch 17 in the upper end of the standard B and connecting with the upper end of the knife guide. The oil dripping from the tube is thus directed into the upper end of the knife guide and effectually 85 lubricates the same and the knife. By this arrangement the discharge end of the feed tube is exposed at the front of the machine where the feed of the oil from the same can be readily seen and the tube can be easily cleared of an obstruction in the event that it should become clogged. The oil cup is located at the side of the machine where it will not interfere with the proper manipulation of the machine or obstruct the operator's view of the work, and as the connection 12 is detachably secured on the frame the oil cup with the connected feed tube can be readily detached and removed 95 when the machine is to be used on material which does not necessitate the lubrication of the knife.

I claim as my invention:

1. In a cloth cutting machine, the combination with an upright standard provided 110

- with a knife guide and a knife which reciprocates in said guide, of lubricating means comprising a lubricant reservoir supported at one side of the standard above the knife 5 guide, and a feed passage leading from the reservoir and having its discharge end arranged adjacent the upper end of the knife for lubricating the same.
2. In a cloth cutting machine, the combination with an upright standard provided with a knife guide and a knife which reciprocates in said guide, of lubricating means comprising a lubricant reservoir supported at an inclination above the knife guide, a feed passage leading from the reservoir and having its discharge end exposed at the front of the machine, and a guide arranged to receive the lubricant from the feed passage and direct it to the knife.
- 10 3. In a cloth cutting machine, the combination with an upright standard provided with a knife guide and a knife which reciprocates in said guide, of lubricating means comprising a lubricant reservoir supported at an inclination above the knife guide, a feed passage leading from the reservoir and having its discharge end exposed at the front of the machine, and a guide groove in the 15 upper end of the standard arranged to receive the lubricant from the feed passage and connecting with the knife guide.
- 15 4. In a cloth cutting machine, the combination with an upright standard provided with a knife guide and a lubricant guide 20 channel in its upper end connecting with the knife guide, and a knife which reciprocates in said guide, of lubricating means comprising a lubricant reservoir supported at an inclination above the knife guide, and a feed passage leading from the reservoir and having its discharge end exposed above the knife guide and arranged to discharge into said guide channel.
- 25 5. In a cloth cutting machine, the combination with an upright standard provided with a knife guide and a knife which reciprocates in said guide, of lubricating means comprising a lubricant reservoir detachably mounted on one side of the machine at an elevation above the knife guide, and a feed tube leading from the reservoir and arranged to discharge the lubricant to the knife guide, said reservoir and feed tube being detachable as a unit from the machine.
- 30 6. In a cloth cutting machine, the combination with an upright standard provided with a knife guide, a frame mounted on the standard, and a knife which reciprocates in said guide, of lubricating means comprising a lubricant reservoir detachably mounted on one side of said frame, and a feed tube leading from the reservoir through said frame and arranged to discharge the lubricant to the knife guide, said reservoir and feed tube being connected and detachable as a unit from the machine.

Witness my hand, this 16th day of September, 1916.

THOMAS SHINGLER.
